UNITED STATES PATENT OFFICE.

CHRISTIAN CHRISTENSEN, OF RYE, NEW YORK.

METHOD OF AND MEANS FOR LAYING OUT BLANKS OF PLAITED ARTICLES.

Application filed April 7, 1922. Serial No. 550,313.

To all whom it may concern:

Be it known that I, CHRISTIAN CHRISTENSEN, a citizen of Germany, residing at Rye, in the county of Westchester and State 5 of New York, have invented certain new and useful Improvements in Methods of and Means for Laying Out Blanks of Plaited Articles, of which the following is a specification.

10 This invention relates to certain new and useful improvements in methods of and means for laying out blanks of plaited articles, particularly valances of window draperies and the like.

15 An object of the invention is to furnish a simple and accurate method for laying out the blanks of a plaited article of known form and dimension whereby valances or the like may be cheaply and easily constructed with the requirement of no especially skilled labor.

20 Another object of the invention is to provide means for enabling an unskilled person to lay out the blank of a plaited article, such as a valance, the invention providing 25 means for denoting the required length or depth of the plaited article and simultaneously denoting the required edge and depth dimension of the blank necessary to 30 construct the plaited article of said predetermined depth.

35 With the above general objects in view and others that will appear as the nature of the invention is better understood, the same consists of the novel form, combination and arrangement of parts hereinafter more fully described, shown in the accompanying drawings and claimed.

40 In the drawings, wherein like reference characters designate corresponding parts throughout the several views,

45 Figure 1 is a front elevational view of a chart or means for laying out blanks of plaited articles constructed in accordance with the present invention and illustrating the method constituting part of the present invention,

50 Figure 2 is a front elevational view of the scale strips employed in the device of Fig. 1,

55 Figure 3 is a view similar to Fig. 1 showing the invention applied to a slightly different form of plaited article, and

Figure 4 is an edge elevational view of the device shown in Fig. 3.

Referring particularly to Fig. 1, the

method of laying out the blanks of a plaited article consists in drawing a vertical base line 5 and a horizontal base line 6, laying off on the vertical base line, as 60 at 7 and 8 respectively, the points for the article depth and the blank depth, a representation, as at 9, of the plaited article being provided upon the chart sheet 10 between the point 7 and the horizontal base 65 line 6, and the vertical base line 5 being disposed at the vertical center of the plaited article when both vertical half sections of said article are similar, as shown.

The top width of the blank is next laid 70 out on the horizontal base line by means of vertical sub-base lines 11 which intersect the horizontal base line 6 at the top of the blank at the points 11'. The extreme width points for the blank are then laid off at 75 opposite sides of the vertical base line 5 as at 12, preferably by means of further sub-base lines which are vertically arranged as at 13 at right angles to the horizontal base line 6. A horizontal bottom width line 80 for the blank is then drawn in the desired direction or directions from the point 8 as at 14. The side edge lines of the blank are then drawn from the ends of the top and bottom width lines of the blank to the extreme width point 12 of the blank as at 15, 85 and then the width of the plaits is laid off along the edge line or lines of the blank where the plaits are to be folded and secured, as at 16. This may be done by indicating uniform or other notches as shown 90 so that when the plaits are formed the points of the V-shaped projections produced will coincide and produce a symmetrical plaited article at the point where the plaits 95 are secured by stitching or the like as is usual in the art. A dimension line is provided as at 17 for the top width of the blank, while a similar dimension line is provided as at 18 for the depth or length of the 100 plaited article and further dimension indicating lines 19 are provided to denote the width of the blank between each sub-base line 11 and the adjacent sub-base line 13 whereby the width of the blank is shown 105 for the space between the extreme width points of the blank and the top width points of the blank. The method of laying out the blank has been described with respect to the pattern or chart sheet from which 110 the measurements and outlines are taken to be drawn upon the fabric from which

the plaited article is to be formed, but as the pattern or chart sheet will be laid out in the same manner as the fabric, the description in connection with the chart sheet 5 rather than the fabric will be clear.

In case the top edge of the article 9 is desired to be drooped slightly, a curved line may be drawn as at 20 to denote the same and as shown in Fig. 1, the greatest distance of sag may be indicated in inches as will also be the case with respect to the length of the bottom width line 14. The lines 11 will be sufficiently spaced apart a greater distance than the top width of the 15 plaited article to allow for this sagging.

The chart sheet 10 is provided with a plurality of pairs of substantially vertical slits as at 21 whereby a plurality of rearwardly directed slide retaining loops are 20 formed for the reception of horizontal slide scales 22 and 23, the slits being provided in the proper places so that when the loops are depressed rearwardly exposure openings for the numerals on the scale strips 23 are formed adjacent the top width indicating line 17, depth line 18, width lines 19 and vertical base line 5 as well as the upper edge lines 15.

It will be noticed that when the plaited article 9 is plaited uniformly at each side of the vertical base line 5, the upper side edge line 15 will be of the same length as the depth line 18 of the plaited article, although terminating above the point 7 because of the line 15 being at an inclination. It will also be noticed that the depth of the blank will always bear a predetermined relation to the depth of the plaited article, and that the distance of projection of the 40 blank between the ends of the top width line of the blank and the extreme width portion of the blank as denoted by the length of the lines, 19 will also bear a predetermined relation with the depth of the plaited 45 article, and for this reason the plurality of slide scales or strips 22 may be rigidly connected at the ends by a binding 24 and thus all be moved simultaneously for exposing a single numeral through each of the exposure 50 openings with the exception of the width indications of the top of the blank, the scales being marked in proper predetermined relation for this purpose as seen clearly in Fig. 2. Thus, by positioning the multiple 55 scale member comprising the bound strips 22 so as to expose the numerals representing in inches the depth of the required plaited article, the remaining dimensions will be exposed through the proper exposure 60 openings, so that the depth of the blank and the like will be immediately indicated. As the top width line of the blank may be indefinitely varied without changing the remaining dimensions for increasing the 65 width of the resultant plaited article, the

scale strip 23 is movable separately from the strips 22 so as to expose the desired measurement adjacent the line 17. The binding 24 may be provided at both ends and tabs may be provided at both ends of the strip 23 as at 25 to be conveniently grasped for adjusting the scale strips so as to expose the desired dimensions through the openings of the sheet 10, the relative positions of the desired numerals upon the scale strip 22 being of a predetermined arrangement as shown clearly in Fig. 2.

The invention may be employed for laying out draperies of many different forms other than that described with respect to

Fig. 1, and an example of one of these remaining forms is shown in Fig. 3 wherein the sheet 10' has the horizontal base line 6' and vertical base line 5' with the representation 9' of the plaited article extending to either side of the line 5' and its point of depth indicated as at 7' on the vertical base line 5'.

The depth point 8' of the blank is also denoted as in Fig. 1 and this is also true of the extreme width line or points of the blank as at 12' assuming that the article is to be plaited uniformly at opposite sides of the vertical center or base line 5'. As previously described, the edge lines of the blank

are drawn in straight lines from the ends of the width line 14' and the ends of the top width line or points 11' to the extreme width points 12'. In this view the vertical sub-base lines 11' are provided in parallel relation at opposite sides of the vertical center or base line 5 to denote the top width line or length of the blank at its top while the distance between said lines 11' and the extreme width points 12' are denoted by the exposure of measurement numerals adjacent the measurement indicating lines 19'.

A similar measurement line 18' is provided for the depth of the article 9' and the sagging of the drapery or article 9' is denoted by the curved top line 20 as in Fig. 1. As the drapery is to be extended to a greater distance at one side of the vertical base line 5 than at the other to provide the extension —a—, it is necessary to enlarge the blank at its lower portion and at that side as denoted by the reference character —b—.

A further sub-base line is vertically provided as at 28 in line with an additional extreme width point 29 provided at this side of the blank, and the distance between the lines 28 and 13' is denoted by the exposure of a measurement numeral near a length indicating line 26 provided between the lines 13' and 28.

The extension of the edge 16' of the blank consists of a line 31 drawn in zig zag fashion from the point 12' at this side of the blank to the point 29 and gaged by a straight line 27 connecting said points, while the adjacent edge line 30 of the blank

is determined by drawing a straight line

from the adjacent end of the bottom width line 14' to the point 29. In this form of the invention the plurality of scale strips or slides 22' are exposed through suitable openings provided by slitting the sheet 10' substantially vertically as at 21' whereby the guide loops 32 for said scale strips are formed. The scale strips 22' are connected to slide together by means of the end bindings or tabs 24' and this may be done by properly arranging the measurement numerals upon the strip 22' in a predetermined relation in view of the fact that the measurements between the lines 18' and 28 and between the points 12' and 29 bear a predetermined relation to the other measurements with the exception of the top width line extending from the left hand point 11^a to the right hand point 11^a. The length of this top width line of the blank may be denoted by the exposure of a numeral on the separate slide strip or scale 23' through an opening provided by slitting the blank as aforementioned, the measurement indicating line being provided at 17' adjacent this opening and the scale strip 23' being provided with end tabs 25'. From the above it will be seen that by setting the multiple scale device comprising the strips 22' and bindings 24' at the proper position so as to expose the depth indicating numeral of the required kind adjacent the line 18' and the depth numeral for the blank adjacent the vertical base line 5', the proper measurement numerals will be exposed for the remaining lines adjacent the measurement indicating lines 19', 17', 27, 26 and 16'.

Various modifications may be resorted to without departing from the spirit and scope 40 of the invention as set forth in the following claims.

What is claimed as new is:—

1. The method of laying out the blank of a plaited article consisting in drawing a vertical base line and a horizontal base line, laying off on the vertical base line the points for the article depth and the blank depth, laying out on the horizontal base line the top width of the blank, laying off extreme width points for the blank at opposite sides of the vertical base line, drawing a horizontal bottom width line of the blank from the vertical base line, drawing the side edge lines of the blank from the ends of the top and bottom width line of the blank to the extreme width points of the blank, and then laying off the width of the plaits along the edge line or lines of the blank where the plaits are to be folded and secured.

2. The method of laying out the blank of a plaited article consisting in drawing a vertical base line and a horizontal base line, laying off on the vertical base line the points for the article depth and the blank depth, laying out on the horizontal base line the top

width of the blank, laying off extreme width points for the blank at opposite sides of the vertical base line, drawing a horizontal bottom width line of the blank from the vertical base line, drawing the side edge lines of the blank from the ends of the top and bottom width lines of the blank to the extreme width points of the blank, drawing vertical sub-base lines at opposite sides of the vertical base line so as to intersect the ends of the top width line of the blank, positioning the extreme width points of the blank a predetermined distance from the last named sub-base lines having a standard relation with the depth measurements of the plaited article and its blank and then laying off the width of the plaits along the edge line or lines of the blank where the plaits are to be folded and secured.

3. The method of laying out the blank of a plaited article consisting in drawing a vertical center or base line and a top horizontal base line, marking extreme width points for the top of the blank and extreme depth lines for the bottom of the plaited article and the blank, drawing a bottom width line for the blank from the vertical base line, drawing vertical sub-base lines at opposite sides of the vertical center or base line so as to intersect the ends of the top width line of the blank, positioning extreme width lines or points for the blank a predetermined distance at opposite sides of the vertical base line a distance apart and a distance from the sub-vertical base lines having a predetermined relation to the depth measurements of the blank and plaited article, then connecting by straight lines the ends of the top and bottom width lines with the extreme width points of the blank and then laying off the width of the plaits along the edge line or lines of the blank where the plaits are to be folded and secured.

4. A means for laying out the blank of a plaited article consisting of a chart sheet having the representation of the plaited article thereon in predetermined relation to the blank from which it may be constructed, and means associated with the chart sheet for indicating the depth of the article and its blank and to simultaneously indicate the distance from opposite sides of vertical center lines intersecting the ends of the top of the blank to the extreme width points of the blank for denoting the position for said extreme width points by a predetermined relation between the article depth and blank depth and the blank width.

5. A means for laying out the blank of a plaited article comprising a chart sheet having the representation of the plaited article thereon and also having the outline of the blank from which said article may be constructed displayed thereon in predetermined relation to said representation of the plaited

4

article, means slidably associated with the chart sheet to denote the blank depth necessary for the construction of a plaited article of a given depth, and means connected with the aforesaid means operable simultaneously therewith for simultaneously denoting the necessary remaining measurements of the blank to form said plaited article.

6. A means for laying out the blank of a plaited article comprising a chart sheet having the representation of the plaited article thereon and also having the outline of the blank thereon from which said plaited article may be formed, with the blank and plaited article representations in predetermined relation, said chart sheet having a horizontal top base line and a vertical center or base line associated with the outline of the blank representation and further sub- 20 vertical base lines intersecting the ends of

the blank top width as well as still further vertical sub-base lines intersecting the extreme width points of the blank, the depth of the plaited article and its blank having a predetermined relation to the distance between the first named sub-base lines and the adjacent extreme width point of the blank, means slidably associated with the chart sheet to indicate the desired depth of the plaited article and blank, and means connected to the slideable means and movable therewith to simultaneously indicate said predetermined relation or distance between the extreme width points of the blank and said first named sub-vertical base lines. 25 30 35

In testimony whereof, I affix my signature.

CHRISTIAN CHRISTENSEN.
